Patented Feb. 24, 1920.

FIG.1

FIG. 2

FIG. 3

INVENTOR

Charles E. Menefee

BY

H. Thornton Bogert

ATTORNEY

UNITED STATES PATENT OFFICE.

CHARLES E. MENESEE, OF NORWOOD, OHIO.

VEHICLE-SPRING LUBRICATOR.

1,331,962.

Specification of Letters Patent. Patented Feb. 24, 1920.

Application filed January 2, 1919. Serial No. 269,318.

To all whom it may concern:

Be it known that I, CHARLES E. MENESEE, a citizen of the United States, residing at Norwood, in the county of Hamilton and State of Ohio, have invented a new and useful Vehicle-Spring Lubricator, of which the following is a specification.

An object of my invention is to produce an improved lubricator for vehicle springs, which will facilitate the placing of a lubricant between the leaves thereof without carrying dust and dirt between them.

A further object is to produce an improved lubricator which will operate to feed fresh lubricant to the spring leaves when the vehicle is in motion, while simultaneously containing a supply of lubricant for operation of the spring over a relatively great period of time.

20 These and other objects are attained in the vehicle spring lubricator described in the following specification and illustrated in the accompanying drawing in which:

Figure 1 is a perspective view of my improved lubricator mounted in position upon a vehicle spring which is shown fragmentally.

Fig. 2 is an underside perspective view of my improved lubricator.

30 Fig. 3 is a perspective view of my improved lubricator showing the condition in which it is supplied to the trade ready for application to the spring upon which it is to be applied.

35 My improved lubricator consists preferably of a strip of sheet metal 4 in conjunction with felt or similar padding 5 which is secured to the spring to be lubricated in the manner to be hereinafter described.

40 The metal portion of the lubricator may be of sheet aluminum, brass or other equally adaptable metal, which is preferably pressed and cut into the shape shown in Fig. 3 with lugs 6 and 7 upon opposite sides of a centrally raised hollow portion 8 and with tongues 9 and 10 upon opposite sides of the strap-like body portion 11. The hollow portion 8 is recessed at its top by pressing the metal into somewhat dished shape while a hole 17 is provided for permitting the introduction of oil therethrough.

Within the raised hollow portion 8 is a block of absorbent material 12 while beneath this pad a strip of absorbent 13 is located which may be formed integrally with the block, or not, as desired.

The assembly of these elements is accomplished by bending lugs 6 and 7 under the felt as shown in Figs. 1 and 3.

In attaching the lubricator to the spring 60 it is but necessary to bend the metal strip around the leaves thereof, with the hollow portion 8 uppermost, until the end 14 which carries the tongues 9 and 10 is overlapped by the opposite end 15. That pair of 65 tongues on opposite sides of strip 11 which are located back of the end 15 sufficiently to leave a portion thereof projecting beyond them, are then bent into overlapping engagement with that end and the projecting 70 portion is in turn bent back over the tongues as shown at 16 in Fig. 2. The remaining ones of tongues 9 and 10 which are not used are then removed from the strip by breaking or cutting. This leaves the lubricator in 75 the position and condition shown in Figs. 1 and 2, with the felt block 12 and strip 13 held in position between the spring leaves and metal strap 11.

The lubricator is prepared for use by injecting enough oil through hole 17 to cause the felt strip 13 and pad 12 to become thoroughly saturated therewith. The action of the lubricator when the felt is thus saturated is to permit the entrance of oil between the leaves largely by capillary attraction, but principally through the pressure exerted upon the upper and under sections of felt when the spring leaves are in action thus squeezing the oil into the vertical sections of felt in contact with the joints between the leaves of the spring. In such an action the section of felt beneath block 12 is saturated with oil from the reservoir block each time the spring leaves return to normal 90 condition.

I have found that my improved lubricator will retain sufficient lubricant for a great mileage and that the lubricant is maintained in good condition at all times, being free 100 from dust and thereby carrying no foreign matter between the spring leaves when it is introduced during the action of the spring. Another feature is that the lubricant is introduced at a point which is always kept 105 free from road dust, thereby avoiding the danger of introducing cutting and wearing substances along with it.

An additional feature of my improved lubricator is that it is designed for use on 110 vehicle springs of varying sizes, the series of lugs 9 and 10 being so located as to permit

of the use of any set thereof in the securing of the lubricator to the vehicle spring.

Having thus described my invention what I claim is:

- 5 1. A vehicle spring lubricator comprising a strip of metal adapted to be bent to embrace a spring to be lubricated and having a hollow projection therefrom, and a lubricant absorbent material located within the projection and surrounding the spring, the top of the hollow projection being depressed to form a trough and having an aperture therein located at the lowest point of the trough.
- 10 2. A vehicle spring lubricator comprising a strip of metal adapted to be bent around a spring to be lubricated, a receptacle upon the strip having means for the delivery of lubricant thereto, transversely extending lugs upon one end of the strip, adapted to be bent across the opposite end of the strip to
- 15
- 20

secure the strip in bent position upon the spring, and lubricant absorbent material within the receptacle and upon the spring embracing surface of the strip.

- 25 3. A vehicle spring lubricator comprising a strip of sheet metal adapted to be bent to embrace a spring to be lubricated and having a hollow projection therefrom, lubricant absorbent material located within the projection and upon the spring embracing surface of the strip, the top of the projection being depressed to form a trough and having an aperture therein at the point of greatest depression, transversely extending oppositely located lugs upon one end of the strip, adapted to be bent toward one another across the strip and upon the opposite end thereof, the opposite end of the strip being adapted to be bent back upon the bent lugs to hold the strip in position.
